UNITED STATES PATENT OFFICE.

THOMAS BOOTH, OF BOISE, IDAHO.

FIRE-ESCAPE.

1,072,814.

Specification of Letters Patent.

Patented Sept. 9, 1913.

Application filed April 23, 1912. Serial No. 692,680.

To all whom it may concern:

Be it known that I, THOMAS BOOTH, citizen of the United States, residing at Boise, in the county of Ada and State of Idaho, have invented certain new and useful Improvements in Fire-Escapes, of which the following is a specification.

This invention relates to fire-escapes and more particularly to that class of such devices which are designed for application to a rope or cable and which include means for frictionally gripping the cable so as to retard the passage of the device along the cable.

It is one aim of the invention to provide a fire escape of this class, so constructed that the person using the same may quickly and readily adjust the device to more or less firmly clutch the rope or cable, depending upon his or her weight.

The invention also aims to provide, in addition to the cable clutching means above referred to, an auxiliary clutch arranged to be manually controlled whereby the person using the escape may readily govern the speed of his or her descent.

The invention aims further to so construct the device that it may be readily applied to and disconnected from the rope or cable and after having been applied will not be liable to become disengaged therefrom.

Another object of the invention is to provide means for adjusting the device for application to cables and ropes of different sizes, or to straps of different thicknesses, where straps are employed in place of the cable or rope.

In the accompanying drawings: Figure 1 is a view in side elevation of the device embodying the present invention; Fig. 2 is a vertical transverse sectional view therethrough, taken in a plane from front to rear; Fig. 3 is a horizontal sectional view on the line 3—3 of Fig. 1; Fig. 4 is a similar view on the line 4—4 of Fig. 1.

Corresponding and like parts are referred to in the following description and indicated in all the views of the accompanying drawings by the same reference characters.

In the drawings the device is illustrated as including, in its construction, a casing having side walls 1 and 2, a front wall 3, and a rear wall 4. The side walls 1 and 2 are connected by the front wall 3, but by referring to Figs. 3 and 4 of the drawings it will be observed that the rear edge of the

side wall 2 terminates short of the rear wall 4, so as to form a slot 5 in one side of the casing. It will also be observed by referring to these two figures of the drawings that the rear wall projects laterally beyond the plane of the side wall 2. The reason for thus forming the walls of the casing will be presently explained.

One of the cable clutching devices of the escape comprises a shoe 6 which is pivoted as at 7 at a point between its ends, the shoe being of a width to extend between the side walls 1 and 2 and having its cable-engaging end projecting downwardly and its upper end projecting upwardly and in the direction of the forward wall 3 of the casing. The cable-engaging face of the shoe 6 is indicated by the numeral 8 and is projected toward the rear wall 4 of the casing. The forward wall of the casing is formed with a slot which is indicated by the numeral 9 and which extends vertically and opens at the lower edge of the said wall.

A lever arm 10 is secured to the forward side of the shoe 6 and projects forwardly therefrom and through the slot 9. This lever arm is provided with an open oblong head, one of the side bars of which is indicated by the numeral 12, and the other by 13. The side bar 13 is formed at intervals with hooks 14 which project upwardly and toward the side bar 12.

A ring 15 is assembled with the head of the lever arm and is interchangeably engageable with the hooks 14, and connected by means of snap hooks 16 to this ring are the upper ends of a looped strap 17 which constitutes a sling in which the person using the escape is supported. In addition to the strap 17 there is provided a belt 18 which is passed around the user's waist and is connected by means of snap hooks 19 to the ring 15. At this point it will be apparent that the rope or cable, to which the device is applied, and which is indicated in the drawings by the reference character R, is to be clutched between the rear wall 4 of the casing and the face 8 of the shoe 6, and it will be readily understood by referring to Fig. 1 of the drawings that, inasmuch as the ring 15 is interchangeably engageable with the hooks 14, and these hooks are located at different distances from the forward wall 3 of the casing, greater leverage will be exerted through the weight imposed upon the lever arm 10 when the ring 15 is engaged

with the outer ones of the hooks than when engaged with the inner ones. When the device is in use, the lever arm 10 will, of course, act to force the shoe 6 firmly against the rear wall 4 of the casing. The person in order to use the device will, of course, engage the ring 15 with that one of the hooks 14 which will so locate the point of application of force to the lever arm as to cause the shoe 6 to sufficiently firmly grip the cable to prevent too rapid descent.

In order that the device may be readily and quickly adapted for use in connection with ropes or cables of various diameters 15 and in order to positively limit the pressure which the shoe 6 may exert against the rope or cable, a set-screw 20 is threaded through the forward wall of the casing and serves as an abutment against which the upper 20 end of the shoe 6 may strike when the lower end of the shoe has moved toward the rear wall of the casing, sufficiently far to properly bind the cable. It will of course be understood that by adjusting the set-screw 20 25 the movement of the cable-gripping face of the shoe 6 in the direction of the rear wall of the casing will be effectually limited.

In addition to the cable-gripping device just described, there is provided a manually controlled auxiliary gripping device, 30 which includes a shoe 21 pivoted at its upper end, as at 22, between the side walls of the casing near the upper end thereof. This shoe 21 is provided with a cable-gripping face 23 which, as in the case of the face 8 of the shoe 6, is extended toward the rear wall 4. The forward wall of the casing is formed with a slot 24 which extends in vertical alinement with the slot 9, and secured 35 to the forward face of the shoe and projecting through the slot 24 is an arm 25. This arm extends forwardly through the slot, and arranged upon the arm at its outer end is a hand grip 27 which may be grasped 40 by the user of the device for the purpose of swinging the arm and imparting similar movement to the shoe 21 to bring the engaging face 23 thereof into engagement with the cable or rope.

From the above, it will be understood 45 that, while the shoe 21 does not normally bear frictionally against the rope or cable, it may be caused to more or less firmly so engage the same by swinging the arm 25 50 downwardly, and it is by doing this that the user of the device is enabled to quicken or retard the speed of his or her descent, at will.

As before stated, the location of the rear

edge of the wall 2, spaced forwardly from the wall 4, results in a slot 5 and it is through this slot that the rope R is to be introduced. In order to restrain the rope R against disengagement from the casing there is provided a cover plate which is indicated by the numeral 28, and is pivoted at its lower end at 29 to the side wall 2 of the casing, and has its upper end bent laterally, as at 30, to form a finger-piece which may be grasped for the purpose of swinging the plate upon its pivot.

As will be apparent from an inspection of Fig. 1 of the drawings, the plate when in position to close the slot 5 has its rear edge resting against the forward face of the 75 projecting portion of the rear wall 4 of the casing, and in order to brace the plate against being swung laterally it is formed at its said rear edge with tongues 31 which project through slots 32 formed in the said 80 rear wall 4. In order to hold the plate 28 against forward swinging movement there is provided a leaf spring latch 33, riveted or otherwise secured to the plate beneath the finger-piece 30, and this latch projects forwardly beyond the plate and near its outer end carries a stud 34 arranged to normally project into an opening 35 formed in the side wall 2.

When the cable or rope is to be engaged 90 in or disengaged from the casing, the latch 33 is swung laterally so as to disengage its stud 34 from the opening 35, and the plate 28 is then swung forward to expose the slot, as shown in Fig. 1 of the drawings in dotted 95 lines, and after such engagement or disengagement the plate is swung back to its original position thereby closing the slot 5.

Having thus described my invention, 100 what I claim as new, is:—

A fire escape comprising a casing, one of the end walls of which extends beyond the adjacent side wall, the side wall being spaced from the more extensive end wall thereby providing an opening through 105 which a cable may be inserted, a plate pivotally supported adjacent the edge of the side wall, said plate being formed with lugs disposed to enter apertures in the end wall, means for locking said plate against movement, and cable engaging means arranged within the casing.

In testimony whereof I affix my signature in presence of two witnesses.
